Primary Examiner—M. N. Pandozzi*Attorney, Agent, or Firm*—Gregory E. Croft**[57] CLAIM**

The ornamental design for a "paper towel," as shown and described.

DESCRIPTION

FIG. 1 is a top plan view of a paper towel showing my new design; and,

FIG. 2 is an enlarged fragmentary perspective view thereof, shown broken away for ease of illustration. Surfaces of the article other than the top surface are not considered to be part of the claimed design.

1 Claim, 2 Drawing SheetsFIG. 1

FIG. 2

Adverse Decisions In Interference

Patent No. D. 382,119, Carlo Ferrero, PAPER TOWEL, Interference No. 104,488, final judgment adverse to the patentee rendered March 14, 2000, as to the sole claim.

(Official Gazette May 2, 2000)
